DESIGN FOR A BATTERY SERVICER

Robert L. Reeves, Akron, Ohio, assignor to The Firestone Tire & Rubber Company, Akron, Ohio, a corporation of Ohio

Application January 19, 1940, Serial No. 89,585

Term of patent 14 years

To all whom it may concern:

Be it known that I, Robert L. Reeves, a citizen of the United States, residing at Akron, county of Summit, and State of Ohio, have invented a new, original, and ornamental Design for a Battery Servicer, of which the following is a specification, reference being had to the accompanying drawing, forming part thereof, in which:

Figure 1 is a perspective view of a battery servicer showing my new design; and

Figure 2 is a plan of the battery servicer shown in Figure 1.

The external appearance of the opposite sides and ends of the battery servicer of my design are the same, so that the side and end of the battery servicer not completely shown are identical with the side and end thereof shown in the drawing.

I claim:

The ornamental design for a battery servicer, as shown, and described.

ROBERT L. REEVES.
